UNITED STATES PATENT OFFICE.

NORMAN JEROME HOAG, OF SKANEATELES, NEW YORK.

SPRING-CONTRACTING DEVICE.

1,113,343.

Specification of Letters Patent.

Patented Oct. 13, 1914.

Application filed November 6, 1913. Serial No. 799,628.

To all whom it may concern:

Be it known that I, NORMAN JEROME HOAG, a citizen of the United States, residing at Skaneateles, in the county of Onondaga and State of New York, have invented certain new and useful Improvements in Spring-Contracting Devices, of which the following is a specification.

This invention relates to improvements in spring contracting devices, designed for use in connection with the valve springs of automobiles and the like.

The stems of the valves of explosion engines as a rule extend outside of the engine cylinders, and spiral springs surround the valve stems for giving the proper tension to the valves. It is frequently necessary to remove the valves for grinding, cleaning or repairing, and in order to do so, the springs must first be compressed, and either held in that condition, or else removed, so that the valves may be released.

The object of the present invention is to provide a novel and simple device, which may be inserted beneath the spring of a valve, and then manipulated for raising and compressing the spring sufficiently to allow the valve and its stem to be removed.

A further object is to provide means for locking and holding the parts of the device in any desired position for maintaining the compression of the spring. And a further object is to provide a device of the class which will first compress and then hold the spring in the proper position until the valve is restored to its working place.

The various features and parts of the invention will be understood from the detailed description which follows, and by reference to the accompanying drawing, in which—

Figure 1 is a top plan view of the device. Fig. 2 is a side elevation; showing the arms of the device spread apart for compressing the spring of the valve; also showing the means for locking said arms in the separated position. Fig. 3 is a similar view; showing the position of the parts of the device before the compressing begins.

In the drawing, 2 represents a portion of the cylinder of an explosion engine, having a raised portion 3, which is bored out at 4 to receive and guide the lower end of the valve stem 5. The upper end of the stem 5 supports the valve 6, and is held in place by a top guide 7, which also comprises a part of

the cylinder 2. Fig. 3 shows the valve 6 seated at 8, and its stem passes through a coil spring 9 in the usual way. The upper end of spring 9 is seated in a cup-washer 10, while its lower end is seated in a similar washer 11, which is held in a certain position on the stem by a pin 12 which pierces the stem, the said pin being employed for holding the spring 9 compressed to a certain extent for exerting the proper tension on the valve 6. When valve 6 and its related parts are in the working condition, the pin 12 rests upon the boss 3. In order to release the valve from the control of the spring 9, so that it may be removed and ground, repaired or cleaned, it is necessary first to lift and compress the spring, so that the pin 12 may be withdrawn, after which the valve and its stem may be removed, as shown in Fig. 2.

The present invention relates to a novel and simple device for compressing the spring, as 9, and comprises similar hinged arms 13 and 14, which are pivoted at 15, which allows their opposite ends to be moved toward or from each other. The free ends of the arms 13 and 14 are formed into relatively broad and thin forks 16 and 17, which are adapted to straddle the valve stem 5, when the device is applied for contracting the spring of the valve. The forked jaws 16 and 17 are moved toward or from each other by means of a handle or lever 18 having a fork 19 which straddles the arm 13 and is pivoted to said arm by a rivet or pin 20. The extreme end of the fork 19 pivotally connects to one end of a link 21, which is pivoted to the arm 14 by a rivet or pin 22. Under this construction, by raising the handle 18 the jaws 16 and 17 are brought together (see Fig. 3) and by lowering the said handle the jaws are spread apart (see Fig. 2). To remove the pin 12 for releasing the valve stem from the control of the spring 9, the handle 18 is raised, and the closed jaws 16 and 17 are inserted between the cup-washer 11 and the top of the boss 3, as shown in Fig. 3. The handle 18 is then depressed, and the jaws 16 and 17 spread apart, as shown in Fig. 2. During this operation the jaw 17 of the arm 14 remains upon the ledge or boss 3, while the jaw 16 of the arm 13 is moved upwardly carrying with it the washer 11 and thereby compressing the spring 9. This upward movement of the washer and spring releases the valve stem and frees the

pin 12 from engagement with the washer 11, so that the engineer may readily withdraw the said pin by the use of a pair of pliers or other suitable instrument 23, as shown in Fig. 2. The valve and its stem are thus released and may be withdrawn from the guides, and repaired, cleaned or ground.

It is a particular object of the present invention to provide a spring contracting device which may be left in the position described during the interval the valve is out of commission, and a further object is to provide means for locking and holding the jaws 16 and 17 in the extended position for maintaining the compression of the spring until the valve is restored to its working position. To this end, I provide a pawl or latch 24, which is pivoted at 25 to the arm 13, the lower end 24' of the pawl normally being in engagement with the top edge of the arm 14, which is provided with a series of ratchet teeth 26, which are arranged directly in the path of the lower end of the pawl 24, so that as the jaws 16 and 17 are spread apart, the pawl 24, which is controlled by gravity traverses and successively engages the said teeth, and thus prevents the jaws 16 and 17 from accidentally closing under the tension of the spring 9. In this manner the spring may be compressed to any desired extent, and the pawl will hold the arms extended. By the provision and arrangement of the pawl 24, the jaws 16 and 17 can be spread apart the requisite distance to enable the engineer to remove the pin 12, and there is no danger of the spring being injured or distorted, and the power of the

spring is at the same time employed for holding the contracting device in place, as shown in Fig. 2, until the valve is returned to its working position. After the valve stem 5 has been inserted in the guides 4 and 7, the pin 12 is placed in position again. The operator should then press downwardly on the handle 18 sufficiently to relieve the strain on the pawl. Then by placing his thumb on the upper end 27, he may swing the pawl from the position shown in Fig. 2 to that shown in Fig. 3. The jaws 16 and 17 will then come together under the power of the spring 9, as shown in Fig. 3. The jaws 16 and 17 may then be withdrawn, which will allow the washer 11 to approach the boss 3.

Having thus described my invention, what I claim as new and desire to secure by Letters Patent, is—

In a device of the class described, a pair of arms hinged at one end, the opposite ends thereof provided with forked jaws, a handle pivoted to the topmost arm, a link connecting said handle to the lowermost arm, a pawl carried by the topmost arm disposed between the handle and one end of said arms, and a series of ratchet teeth arranged on the lowermost arm and engaged by said pawl for adjustably holding said jaws apart, substantially as described.

In testimony whereof I affix my signature in presence of two witnesses.

NORMAN JEROME HOAG.
